UNITED STATES PATENT OFFICE.

WILLIAM THOMAS DUNN, OF ROCKAWAY, NEW JERSEY, ASSIGNOR TO INTERNATIONAL HIGH SPEED STEEL COMPANY, OF NEW YORK, N. Y., A CORPORATION OF NEW YORK.

CORE-REMOVING APPARATUS.

1,283,702.

Specification of Letters Patent.

Patented Nov. 5, 1918.

Application filed June 19, 1917. Serial No. 175,579.

To all whom it may concern:

Be it known that I, WILLIAM THOMAS DUNN, a citizen of the United States of America, residing at Rockaway, Morris county, State of New Jersey, have invented new and useful Improvements in Core-Removing Apparatus, of which the following is a specification.

This invention relates to core removing apparatus.

The object of the invention is to provide an efficient apparatus for rapidly removing the sand core from the bars used in making tubular drills of steel. A further and more specific object is to provide in such an apparatus a drilling element which is self sharpening and in the use of which air under a very low degree of compression may be used.

The invention consists of the construction, combination and arrangement of parts, as herein illustrated, described and claimed.

In the accompanying drawing, forming part hereof, is illustrated a form of embodiment of the invention, in which drawing similar reference characters designate corresponding parts, and in which:

Figure 1 is a plan view;

Fig. 2 is a side elevation;

Fig. 3 is a side elevation partly in section of a billet from which tubular drill bars are drawn;

Fig. 4 is a side elevation partly in section of the drill bar after being drawn; and

Fig. 5 is a side elevation of the cutting end of the drilling elements of the apparatus herein described.

In the making of tubular bars for the manufacture of tubular drills, a billet 21 of steel is first provided with a bore 22 and the bore 22 is filled with sand or similar silicious material 23. Plugs 24 are secured in the ends of the bore 22 and the billet 21 is then heated in a furnace and afterward subjected to the action of a rolling apparatus so that it becomes elongated, as best shown in Fig. 4. During this rolling operation the body of silicious matter 23, under the action of heat and pressure incident to the rolling operation, becomes very closely packed and vitrified. The removal of this core in the drill bar has presented difficulties to the manufacturer in that no efficient means has come into public use for rapidly removing the core 23, which, owing to its nature, resists the action of even the hardest drill so that

the ordinary drill becomes dull before the entire bore is traversed. It is to overcome this difficulty that the present invention was made.

As best shown in Figs. 1 and 2, a base 1 has disposed thereover a framework 2, comprising in part a cross bar 3, through which pass the bars 4 from which the cores 23 are to be removed. The bars 4 rest upon grooved rollers 5, carried by the framework and are pushed or otherwise conveyed downward on the framework 2, so that the drilling element 14, hereinafter described, passes entirely through the bore 22 and removes the core 23.

A suitable motor 6 is disposed adjacent one end of the frame 2, preferably on the base 1, and is arranged to run a belt 7, disposed over a pulley 8, on a shaft 9. The shaft 9 is disposed in bearings 10 on the lower end of the frame 2 and carries pulleys 11. Suitable belts 12 are disposed over the pulleys 11 and over pulleys 13 arranged to rapidly rotate the drill 14. The position of the drill 14 coincides with the axes of the bars 4 and the lengths of the drills are greater than the bars 4 to be drilled.

A pipe 15 is carried by one end of the framework 2 and is connected to a suitable source of air supply under a very low degree of compression. Pipes 17 are connected to the drills 14 and to the pipe 15, a suitable form of stuffing box being used. The air passing through the pipe 17 may be controlled by suitable valves 18.

The lower end of the framework 2 is pivotally connected to the base 1, so that different degrees of inclination may be obtained, suitable telescoping supporting legs 19 being attached to the frame 2, and set 95 screws 20 being used to fix the height of the supporting legs 19.

The external diameter of the drills 14 is the same as the bores 22 of the bars 4. At the cutting end of the drills 14, an outside 100 tapered portion 25 is formed terminating at the wall of the bore 22^a to form a cutting edge (see Fig. 5). In the operation of the apparatus, the drills 14 being rapidly rotated, the tapered portion 25 is gradually 105 worn back by attrition of the vitrified core 23 of the bars 4. In forming the taper 25, the wall of the bore 22^a of the drill 14 forms a cutting edge of less diameter than the bores 22 of the bars 4, and as the drills 14 rapidly 110

rotate the air under a slight compression blows back the disintegrated vitrified core 23. To adjust the feed, the frame 2 may be raised or lowered and fixed in any desired 5 position by the set screws 20 and legs 19.

Having thus fully described my invention, what I claim as new and desire to secure by Letters Patent is:

1. A core removing apparatus comprising 10 an inclined work-supporting frame, a plurality of drills disposed at one end of the frame and means for rotating the drills.
2. A core removing apparatus comprising a work-supporting frame, means for fixing 15 the frame at varying degrees of inclination, a plurality of drills carried by the frame at one end and means for rotating the drills.
3. A core removing apparatus comprising a work-supporting frame, telescoping sup- 20 porting legs arranged to support the frame, set screws arranged to secure the legs at a plurality of heights to vary the movement of the work on the frame, a plurality of drills carried by the frame and means for 25 rotating the drills.
4. A core removing apparatus comprising an inclined frame, a plurality of drills car-

ried by the frame, means for rotating the drills and means for guiding bars to the drills.

5. A core removing apparatus comprising a frame, a plurality of drills carried by the frame, means for rotating the drills and a plurality of grooved rollers on the frame in alignment with the drills.

6. A core removing apparatus comprising a work-supporting frame, a plurality of drills carried by the frame, means for rotating the drills and means for admitting compressed air through the drills.

7. A core removing apparatus comprising a work-supporting frame, a plurality of tubular drills carried by the frame and provided with tapered ends and means for rotating the drills.

8. A core removing apparatus comprising an inclined work-supporting frame, a plurality of tubular drills having tapered ends and rotatably supported on the frame, means for admitting compressed air through the 50 drills and means for rotating the drills.

In testimony whereof I have signed my name to this specification.

WILLIAM THOMAS DUNN.
